UNITED STATES PATENT OFFICE.

ALBERT T. BISHOP, OF SOUTHBINGHAM, CONNECTICUT.

DESIGN FOR A CAN-OPENER.

SPECIFICATION forming part of Design No. 22,348, dated April 11, 1893.

Application filed February 1, 1893. Serial No. 460,613. Term of patent 7 years.

To all whom it may concern:

Be it known that I, ALBERT T. BISHOP, a citizen of the United States, residing at Southington, in the county of Hartford and State of Connecticut, have invented and produced a new and original Design for a Can-Opener, of which the following is a specification, reference being had to the accompanying drawings, in which—

Figure 1 is a perspective view of a can-opener showing my design, and Fig. 2 is a side elevation, showing the rear side of the same.

A, designates the handle which is somewhat flattened toward the outer end 3 and also curved in scroll form as shown. The head 4 is provided with a curved blade 5, sharpened

on its convex edge 6. The inner lower corner of the head is rounded and provided on its front side with a rounded laterally projecting boss 7, and on the other side with a ²⁰ forwardly projecting and pointed lip 8, the face of said lip on that side which is nearest the blade being flat and parallel to said blade as shown in Fig. 1, while its opposite side is rounded off as shown in Fig. 2.

What I claim is—

The design for a can opener as herein shown and described.

ALBERT T. BISHOP.
